United States Patent Office

Des. 184,535
Patented Mar. 3, 1959

184,535

COMBINED GYMNASIUM AND TEETER

Marlan H. Polhemus, Royal Oak, Mich., assignor to
Trimble, Inc., Rochester, N. Y., a corporation of New
York

Application July 16, 1958, Serial No. 51,811

Term of patent 14 years

(Cl. D34—5)

FIG.1

FIG.2

Fig. 1 is a perspective view of a combined gymnasium and teeter showing my new design; and

Fig. 2 is an inverted view thereof.

I claim:

The ornamental design for a combined gymnasium and teeter, substantially as shown.
